LLC**CLAIM**

The ornamental design for an agricultural machine, as shown and described.

DESCRIPTION

FIG. 1 is a perspective view of an agricultural machine with spray booms, each in a folded, transport position;

FIG. 2 is a left side elevational view of the agricultural machine as in FIG. 1;

FIG. 3 is a right side elevational view of the agricultural machine as in FIG. 1;

FIG. 4 is a front elevational view of the agricultural machine as in FIG. 1;

FIG. 5 is a rear elevational view of the agricultural machine as in FIG. 1;

FIG. 6 is a top plan view of the agricultural machine as in FIG. 1; and,

FIG. 7 is a bottom plan view of the agricultural machine as in FIG. 1.
